CLAIM

The ornamental design for a nozzle for welding torch, as shown and described.

DESCRIPTION

FIG. 1 is a left front perspective view of a nozzle for welding torch showing our design;

FIG. 2 is a front elevational view of the nozzle of FIG. 1;
FIG. 3 is a rear elevational view of the nozzle of FIG. 1;
FIG. 4 is a left side view of the nozzle of FIG. 1;
FIG. 5 is a right side view of the nozzle of FIG. 1;
FIG. 6 is a top plan view of the nozzle of FIG. 1;
FIG. 7 is a bottom plan view of the nozzle of FIG. 1;
FIG. 8 is a left front perspective view of another embodiment of a nozzle for welding torch showing our design;
FIG. 9 is a front elevational view of the nozzle of FIG. 8;
FIG. 10 is a rear elevational view of the nozzle of FIG. 8;
FIG. 11 is a left side view of the nozzle of FIG. 8;
FIG. 12 is a right side view of the nozzle of FIG. 8;
FIG. 13 is a top plan view of the nozzle of FIG. 8; and,
FIG. 14 is a bottom plan view of the nozzle of FIG. 8.
The broken lines show portions of a nozzle for welding torch which form no part of the claimed design.
